UNITED STATES PATENT OFFICE.

DEWITT C. HARLOW, OF HANNIBAL, MISSOURI, ASSIGNOR TO HIMSELF AND
NORMAN H. WILLIAMS, OF SAME PLACE.

IMPROVEMENT IN CLOTHES-PINS.

Specification forming part of Letters Patent No. 129,950, dated July 30, 1872.

SPECIFICATION.

To all whom it may concern:

Be it known that I, DEWITT C. HARLOW, of Hannibal, in the county of Marion, in the State of Missouri, have invented certain Improvements in Clothes-Pins; and do hereby declare that the following description, taken in connection with the accompanying plate of drawing, hereinafter referred to, forms a full specification of the same, wherein I have set forth the nature and principles of my said invention, by which it may be distinguished from others of a similar class, together with such parts as I claim and desire to secure by Letters Patent.

My invention relates to that class of clothes-pins which are actuated by a spring, and the nature thereof consists in certain improvements in the details of the construction of the same, hereinafter described and shown.

In the accompanying drawing, which illustrates my invention and forms a part of the specification thereof, Figure 1 is a side view of the said clothes-pin when the parts thereof are closed, and Fig. 2 is a view of same with the parts opened.

The construction and operation of my invention are as follows:

In the drawing referred to, A A' represent the jaws, of similar size and shape. On each side of the said pin are the springs B, of the form shown, consisting of a coil, the ends of which cross each other, and are so bent as to pass through the jaws in apertures cut therein parallel with each other.

The pin may be manufactured with great cheapness and facility, from the fact that the springs are arranged altogether on the outside thereof, in such a manner that it is only necessary to bore holes upon the exterior of the pin to secure the said springs in position.

By this construction a pin is formed which has no hinge at the fulcrum to hold the parts together.

I claim—

A clothes-pin, consisting of the jaws A A and spring B, arranged upon the exterior surface of the said jaws, as and for the purposes described.

In witness whereof I have subscribed my name hereto this 13th day of February, 1872.

DEWITT C. HARLOW.
